UNITED STATES PATENT OFFICE.

CHARLES C. CLIFFORD AND CLARENCE J. MOTT, OF COLDRAINE, MINNESOTA.

REVOLVING GRIZZLY.

1,408,799.

Specification of Letters Patent.

Patented Mar. 7, 1922.

Application filed April 29, 1921. Serial No. 465,396.

To all whom it may concern:

Be it known that we, CHARLES C. CLIFFORD and CLARENCE J. MOTT, both citizens of the United States, residing at Coleraine, in the county of Itasca and State of Minnesota, have jointly invented certain new and useful Improvements in Revolving Grizzlies, of which the following is a specification.

This invention relates to a new and improved revolving grizzly. More specifically, it involves a grizzly particularly adapted for the elimination of the larger fragments through the action of the grizzly itself, thus avoiding the necessity for hand labor.

In the handling of ores, coal or similar materials, it is customary to provide grizzlies or similar devices adapted to eliminate the larger fragments from the material. The smaller fragments passing through the grizzly may be carried to screens or passed on to other apparatus to carry out any desired process. Where the grizzlies consist simply of a series of bars or rods, the larger fragments striking the grizzlies and failing to pass through tend to remain thereon, and it is necessary to provide one or more men to remain adjacent the grizzly to remove these larger blocks. If a number of these large fragments come down at the same time it causes a great deal of work and may cause delay to the feed of the mill.

It is an object of the present invention to provide a grizzly so constructed as to automatically eliminate the larger chunks of material which fail to pass through the grizzly.

It is a further object to provide grizzlies adapted to pass these larger chunks to bins separate from the bins or chutes to which the small material passes through the grizzly.

It is also an object to provide a device of this character which is rugged and adapted to stand up under the heavy duty which such an apparatus undergoes.

It is an additional object to provide a device which is simple in design and efficient in operation.

Other and further objects will appear as the description proceeds.

Broadly, our device comprises a plurality of parallel bars, preferably octagonal in cross section, the bars being placed in two series rotating in opposite directions from

the center and each series composed of bars successively lower in elevation from the center outward.

We have illustrated a preferred embodiment of our invention in the accompanying drawings, in which—

Figure 1 is a plan view of the grizzly and its driving mechanism;

Figure 2 is a somewhat diagrammatic side view of the grizzly and its driving mechanism;

Figure 3 is an end view of the grizzly; and

Figure 4 is a section on line 4—4 of Figure 1.

As shown in the drawings, the grizzly comprises two end frames 4 and 5 in which are journaled two series of parallel octagonal bars. The centrally located bars 6 and 7 are at a higher level than the adjacent bars 8 and 9 respectively, and the outer bars 10 and 11 are at a still lower level. The bars 6 and 7 are directly connected to the gear wheels 12 and 13 which are in mesh with each other and with the driving gear 14. The bars 6 and 7 are further provided with the sprocket wheels 15 and 16 which are connected by chains 17 and 18 to the sprocket wheels 19 and 20 which are carried by the grizzly bars 8 and 9 respectively. These bars 8 and 9 carry sprocket wheels 21 and 22 which are connected by chains 23 and 24 to the sprocket wheels 25 and 26 carried by the grizzly bars 10 and 11.

The driving apparatus as shown comprises the electric motor 27 whose pulley 28 is connected to the main drive pulley 29 by the belt 30. This belt 30 is tensioned by the idler pulley 31. The shaft of the main drive pulley 29 carries the gear wheel 32 which is in mesh with the reduction gear 33. This gear 33 is upon the same shaft as the drive gear 14.

The discharge chute 34 extends below the grizzlies at an angle as shown in Figure 2, and the feed chute 35 leads from the ore bin to the grizzly. Lateral bins 36 as indicated in Figure 1 may be provided upon either side of the grizzly to receive the larger chunks of material.

As shown in Figure 4, the bars of the grizzly comprise a center shaft 40 and a plurality of paired enclosing wear members 41, held together by rivets 42.

In the operation of our device, the motor

serves to rotate the drive gear 14 through the gearing as shown, and this gear 14 serves to rotate the gear wheels 12 and 13 and consequently the grizzly bars 6 and 7 in opposite directions, the upper surface of the bars moving outwardly and away from each other. The sprocket and chain connection between each series of bars is such that the bars upon each side of the center rotate in the same direction. The material coming down the chute 35 and falling upon the grizzly bar is agitated by the rotation of the octagonal bars and pieces of the material smaller in dimension than the clearance between the bars will fall through the spaces between them and be carried by gravity down the chute 34. The larger pieces of material are carried laterally by the turning movement of the grizzlies, the upper surfaces of which move toward the outer edge of the grizzly, and later fall into the bins 36.

The slope of each series of bars is comparatively gradual in order that the smaller material may have full opportunity to fall through the bars before it can be carried over the side, and yet the slope is sufficiently great to carry the larger pieces over the side before they will tend to pile up at the far end of the bars. The fact that the bars are octagonal in shape is of material importance in handling these larger pieces and giving them their lateral movement. Rounded bars would fail very largely to give this movement, since they would have no surfaces or edges adapted particularly to engage the large pieces, while bars provided with large flat surfaces would tend to jam or crush the larger pieces between adjacent bars, which is not a function of the grizzlies.

The bars of the grizzly are subject to considerable wear due to the impact of the heavy pieces of ore and the movement of these pieces over the bars. For this reason the bars are formed as the composite structure shown with the enclosing members formed of manganese steel or similar wear-resisting material.

Preferably, as shown in Figures 1 and 2, these enclosing members consist of a plurality of short sections. The wear is greatest upon the upper end of the grizzly and when that section of the member is worn out, its rivets may be knocked or burnt out and the section removed. A new section may be placed at that point or the old sections may be slipped up on the bar and the new section placed on the lower end of the bar.

The device as shown is very efficient in eliminating larger pieces or separating them from the finer material, and is important in that it avoids considerable hand labor and any possibility of delay or trouble in the attempt to remove these larger pieces by manual labor.

While we have shown a preferred form of the device, it is to be understood that many variations in the form and relation of the parts will be required for varying types of material and methods of feed and discharge. We reserve the right to make any such changes or modifications as may come within the spirit of our invention and the scope of the appended claims.

We claim:

1. In combination with means for feeding material thereto, a grizzly comprising a plurality of laterally spaced bars extending approximately parallel with the line of flow of the material from the feeding means to the grizzly, and means adapted to rotate said bars, the bars being divided into two oppositely rotating series, each series rotating in such manner that the upper surfaces of the bars move outwardly from the center, the outer bars of each series being upon a lower level than the adjacent bars.

2. In combination with means for feeding material thereto, a grizzly comprising a plurality of laterally spaced bars, extending approximately parallel with the line of flow of the material from the feeding means to the grizzly, and means adapted to rotate said bars, the bars being divided into two oppositely rotating series and rotating in such manner that their upper surfaces move outwardly from the center, the outer bars of each series being upon a lower level than the adjacent bars, and the innermost bars of each series being upon a higher level than the adjacent bars.

3. In combination with means for feeding material thereto, a grizzly comprising a plurality of laterally spaced octagonal bars extending approximately parallel with the line of flow of the material from the feeding means to the grizzly, and means adapted to rotate said bars, the bars being divided into two oppositely rotating series and rotating in such manner that their upper surfaces move outwardly from the center, the outer bars of each series being upon a lower level than the adjacent bars, and the innermost bars of each series being upon a higher level than the adjacent bars.

4. In combination with means for feeding material thereto, a grizzly comprising a plurality of adjacently arranged octagonal bars extending approximately parallel with the line of flow of the material from the feeding means to the grizzly, and means adapted to rotate said bars, said bars being divided into two series located in intersecting planes, each series being located in a plane sloping outwardly and downwardly from the intersection of the two planes.

5. In combination with means for feeding material thereto, a grizzly comprising a plurality of laterally spaced octagonal bars extending approximately parallel with the

line of flow of the material from the feeding means to the grizzly, and means adapted to rotate said bars, said bars being divided into two series, each series being located in a plane sloping outwardly and downwardly from the intersection of the two planes, the bars in each series rotating in such manner that their upper surfaces move outwardly from said intersection.

10 6. In combination with means for feeding material thereto, a grizzly comprising a plurality of laterally spaced bars, each bar extending approximately parallel with the line of flow of the material from the feeding means to the grizzly comprising a central shaft and enclosing wear members secured thereto, said wear members comprising rela-

tively short sections forming rings encircling the bar.

7. In combination with means for feeding material thereto, a grizzly comprising a plurality of laterally spaced bars, each bar extending approximately parallel with the line of flow of the material from the feeding means to the grizzly comprising a central shaft and enclosing wear members secured thereto, said wear members being formed in a plurality of sections divided transversely of the bar, encircling the bar and fitting slidably thereon. 30

Signed at Coleraine, Minnesota, this 24 day of March, 1921.

CHARLES C. CLIFFORD.
CLARENCE J. MOTTE.
